UNITED STATES PATENT OFFICE.

VICTOR LINDER, OF ELKO, MINNESOTA.

DOOR AND GATE ACTUATING MECHANISM.

1,391,685.

Specification of Letters Patent. Patented Sept. 27, 1921.

Application filed November 24, 1919. Serial No. 340,272.

To all whom it may concern:

Be it known that I, VICTOR LINDER, a subject of the King of Sweden, residing at Elko, in the county of Scott and State of Minnesota, have invented certain new and useful Improvements in Door and Gate Actuating Mechanisms; and I do hereby declare the following to be a full, clear, and exact description of the invention, such as will enable others skilled in the art to which it appertains to make and use the same.

My invention relates to improvements in door and gate actuating mechanism, and, to this end, it consists of the novel devices and combinations of devices hereinafter described and defined in the claims.

In the accompanying drawings, which illustrate the invention, like characters indicate like parts throughout the several views.

Referring to the drawings:

Figure 1 is a plan view of the invention; Fig. 2 is a longitudinal vertical section taken on the line 2—2 of Fig. 1; and

Fig. 3 is a detail view with some parts shown in section taken on the line 3—3 of Fig. 2 with the adjacent door open.

The numeral 4 indicates double swinging doors or gates hinged at their outer vertical edges to posts 5 for horizontal swinging movement. The posts 5 are tied together by a sill 6 and a top bar 7. Each door 4 is closed by a coiled spring 8 anchored at one of its ends to the upper edge of the respective door and at its other end to the top bar 7. A spring-projected lock-bolt 9 is provided for locking each door closed. The casings of these lock-bolts 9 are secured to the inner faces of the doors 4 near their free vertical edges at the tops thereof for engagement with lock-plates 10 secured to the under face of the top bar 7.

On each side of the doors 4 are outer and inner transverse sills 11 and 12, respectively.

To the outer ends of each sill 11 is secured a pair of posts 13 and to the outer ends of each sill 12 is secured a pair of posts 14. All of the posts 5, 13 and 14, on each side of the road, are connected by longitudinal rails 15 secured to the tops of the posts 13 and 14.

To each sill 12 is secured bearings 16 in which are journaled a pair of door-opening and lock-releasing cranks 17 arranged in the wheel tracks to be engaged by the wheels of a moving vehicle. Cables 18 connect the

cranks 17 to eyes 19 secured in the front faces of the doors 4. These cables 18 are extended through guide eyes 20, on the rails 15, and are of such length as to hold the crank 17 raised when the doors 4 are closed. 60 To release the lock-bolts 9, branch cables 21 have one of their ends attached to the lower ends of said lock-bolts and their other ends are attached to the cables 18 near the eyes 19. The length of the branch cables 21 is 65 such that the spring-held lock-bolts 9 lift the cables 18 a little so that the initial downward movement of the cranks 17, by the engagement of vehicle wheels therewith, will release said lock-bolts, and further downward movement of said cranks will open the doors 4 through the cable connections 18 and tension springs 8.

To hold the doors 4 open against the action of the springs 8, while a vehicle is passing therethrough, spring-actuated latches 22 are pivoted in bearings 23 on the rails 15 and arranged to engage latch-plates 24 on the free edges of said doors. Each latch 22 is provided with a crank arm 25 to which is 75 attached two oppositely extended cables 26. The outer ends of the cables 26 are attached to latch-releasing cranks 27 journaled in bearings 28 secured to the sills 11 and extend through guide eyes 29, certain of which are arranged to cause said cables to give a downward pull on the cranks 27 when the wheels of a vehicle pass over said cranks 27 to lift the latches 22 out of engagement with the latch-plates 24. In place of the guide 80 eyes 20 and 29, guide sheaves may be substituted therefor.

It will be noted that the throw of the cranks 27 is considerably less than that of the cranks 17 and are located sufficiently 95 outward from said cranks 17 to permit a vehicle to stand therebetween without engaging the cranks 17 and 27. A vehicle passing toward the doors 4, for instance from the left in respect to Fig. 2, will first pass over 100 the left-hand cranks 27 and operate the latches 22, which, of course, is an idle movement as the doors 4 are closed. Further movement of the vehicle toward the doors 4 will cause its wheels to pass over the cranks 105 17 and, as previously stated, the initial downward movement thereof, through the cables 18 and 21, will release the lock-bolts 9, and a further downward movement of said cranks 17 will swing the doors 4 open 110

and cause the same to be held open by the automatic interlocking engagement of the latch-plates 24 with the latches 22. After the vehicle has passed through the door-opening, its wheels will pass over the right-hand cranks 17, which, in this case, will be down, for the reason that the doors 4 are open. A further advanced movement of the vehicle will cause its wheels to pass over the right-hand cranks 27 and the downward movement thereof will release the latches 22 from the latch-plates 24 through the cables 26 and thereby permit the doors to be swung closed under the action of the springs 8. A vehicle moving in the opposite direction from that just described will, of course, release the lock-bolts 9 and open the doors 4 by the depression of the right-hand cranks 17 and release the latches 22 to permit the doors to close by the depression of the left-hand cranks 27.

What I claim is:—

1. A door actuating mechanism comprising a post, a door extending therefrom and hinged thereto at one side, a raised rail normally extending longitudinally to the plane of the door when in closed position, a sill extending transversely to said rail at some distance from said door at each side thereof, upstanding cranks pivoted on said sills, the ends of the cranks extending to a point substantially below said rail, guiding means on said rail, one above the end of each crank member, a pair of guiding means on said rail adjacent the hinged side of said door, a cable for each crank member having its end attached to the end thereof, passing through the guiding means thereabove and through one of the guiding means adjacent the door having its other end attached to said door adjacent the hinge thereof, and spring means tending normally to close the door.

2. A door operating mechanism comprising a post, a door extending therefrom and hinged thereto at one edge, a sill extending across the top of said door, vertically movable lock member on said door taking into said sill, a raised rail extending longitudinally along the side of said door, a sill at each side of said door extending transversely of said rail, upstanding crank members pivoted to said sills, guide members on said rail, cables attached to the end of said crank members passing through the guiding means on said rail and secured to the door adjacent the hinge thereof, and a pair of auxiliary cables attached to said first mentioned cables adjacent the point where they are secured to the door and secured at their other ends to said lock members, spring means tending normally to close the door and spring means tending normally hold the locks in the

sills and also acting to lift the first mentioned cables whereby, a movement of the crank will first release the lock bolts and further movement thereof will open the door.

3. A door actuating mechanism comprising a post, a door extending therefrom and hinged thereto at one edge, a rail extending longitudinally along the side of said door and post, a pair of spaced sills at each side of the door extending parallel to the same in its closed position, an upstanding crank member pivoted to each of said sills, guiding means on said rail and cables attached to the ends of the crank members on the sills nearest the door extending through said guiding means and attached to said door, a spring pressed latch pivoted on said rail and disposed to engage the door when in fully open position to hold the same in open position, a latch operating arm connected to said latch, a second set of guiding means on said rail, and cables attached to the crank members on the outer sills extending through said guiding means and attached to the latch operating arm.

4. A door operating mechanism having in combination a pair of vertical posts, doors extending between said posts and pivoted thereto at one edge, a sill extending across the top of said doors and secured at its ends in said posts, raised rails extending longitudinally at each side of said posts and normal to said sill, a pair of transverse sills adapted to be disposed on the ground or floor at each side of said post and parallel to the first mentioned sill, a pair of oppositely disposed crank members pivoted for swinging movement on each of said sills, the ends of said crank members extending substantially under said rails, guiding means on the inside of said rails and guiding means on the outside of said rails, cables attached to the ends of the cranks on the sills nearest the doors and extending through the guiding means on the inside of the rail and attached to each door, pivoted latches mounted on each rail and adapted to engage the door and hold the same in open position and cables attached to the ends of the cranks on the outer sills and passing through the guiding means on the outside of the rails and secured to arms extending from said latch means and springs normally tending to close said door.

In testimony whereof I affix my signature in presence of two witnesses.

VICTOR LINDER.
